BINDING ELEMENT

Charles Edward Emmer, Chicago, Ill., assignor to
General Binding Corporation, Chicago, Ill., a
corporation of Illinois

Application October 9, 1943, Serial No. 505,617

6 Claims. (Cl. 281—21)

1

This invention relates to bindings, and more particularly to bindings formed of vinyl resin, Celluloid or other plastic materials, as well as to those formed of fiber material, including paper or the like.

One general type of mechanical binding which is employed to bind the leaves of books, magazines, calendars, etc., together, is a binding formed of a resilient plastic material such as Celluloid, which comprises a series of rings which integrally extend from a common backbone through loose fitting holes along the edges of the pages or sheets. These mechanical bindings are coming into wide use particularly for binding catalogues, sales presentation literature, magazines of the better class and similar publications, because of their attractive appearance and the ability of books bound with them to lie flat when open.

It is an object of the present invention to provide a novel mechanical binder.

Another object of the present invention is to provide a novel binder having a backbone and a plurality of integral fingers extending therefrom.

A further object of the present invention is to provide a novel plastic binding.

Another and further object of the present invention is to provide a novel plastic binder including a backbone and a plurality of integral fingers extending therefrom, one surface of each finger having a plurality of transverse lightly scored lines thereon to enable the finger to be readily bent in arcuate form and a pair of relatively heavy scored lines to enable a sharp bend to be made in the finger in proximity to the backbone and also in proximity to the tip of the finger.

Still another object of the present invention is to provide a binding blank or partially formed binding element having pressure-sensitive adhesive on a portion thereof which may be closed and secured in book binding form without the aid of any additional binding element or without the aid of machinery.

The novel features which I believe to be characteristic of my invention are set forth with particularity in the appended claims. My invention itself, however, both as to its organization and manner of construction, together with further objects and advantages thereof, may best be understood by reference to the accompanying drawings, in which:

Figure 1 is a plan view of a blank of material illustrating how two comb-shaped forms may be stamped therefrom and also illustrating how the fingers of at least one blank may be transversely scored in accordance with the teachings of the present invention;

Figure 2 illustrates a portion of a comb-shaped

2

form after it has been stamped, scored and removed from the original blank of plastic material;

Figure 3 is an isometric view of a portion of the plastic binder after the fingers of the comb-shaped form shown in Figure 2 have been bent in desired arcuate form;

Figure 4 is a view similar to Figure 3, but shows the plastic binder turned over and a pressure-sensitive adhesive applied to the base portion thereof;

Figure 5 is an isometric view of a portion of the cover of a book or the like having front and rear covers and a back whose inner surface is covered with a pressure-sensitive adhesive;

Figure 6 shows the plastic binding of Figures 3 and 4 mounted within the covers and back of the book shown in Figure 5;

Figure 7 is an end view of a modified form of plastic binder and back plate;

Figure 8 is a view similar to Figure 2 showing a different embodiment of the present invention;

Figure 9 is a transverse sectional view of a plastic binder formed from the comb-shaped form of Figure 8;

Figure 10 is an isometric view showing a different form of binding element partially curled and ready to receive a stack of sheets to be bound;

Figure 11 is an end view of the binding element of Figure 10 after a stack of sheets has been mounted thereon, and after the binding element has been closed and secured by a pressure-sensitive adhesive;

Figure 12 is an isometric view similar to Figure 10 showing a different form of binding element;

Figure 13 is an end view of the binding element of Figure 12 after a stack of sheets has been mounted thereon, and the binding element has been sealed by pressure-sensitive adhesive;

Figure 14 is an isometric view similar to Figure 10 showing a different form of binding element partially curled and ready to receive a stack of sheets to be bound; and

Figure 15 is an end view of the binding element of Figure 14 after a stack of sheets has been mounted thereon and the binding element closed and secured by a pressure-sensitive adhesive.

In Figure 1 of the drawings there is shown a blank 10 of plastic, fiber or other suitable material which has been stamped and scored to form two comb-shaped elements 11 and 12, and in order that the fingers of each comb-shaped element may be more distinctly and quickly observed, the scoring lines have been omitted from the fingers of the element 12. It will be understood, however, that each of the elements includes a backbone 13 and a plurality of fingers 14. Simultaneously with the stamping operation

which cuts the comb-shaped elements from a blank of suitable material, one surface of the fingers 14 is provided with a plurality of lightly scored transversely extending lines 15 (see Figure 2). These lightly scored lines on one surface of each of the fingers extends over the area which is presently to be bent into arcuate or semi-circular form. In addition to the light transversely extending scores 15 there is provided a pair of relatively heavy scored lines 16 and 17 at the ends of the area of lightly scored lines. The relatively heavy scored line 16 is located adjacent the backbone 13 while the relatively heavy scored line 17 is located in proximity to the end of the fingers 14 but spaced slightly back therefrom. These relatively heavy scored lines 16 and 17 are for the purpose of permitting a sharp bend in the material at this point without the use of heat or other extraneous means, while the lightly scored lines are for the purpose of permitting the ready bending of the intermediate portions of the fingers without the use of heat or other extraneous means.

The edge of the backbone 13 which lies opposite to the edge from which the fingers 14 extend is provided with a series of notches or cut out portions 18 which correspond in number to the number of fingers and which lie directly opposite the fingers on the backbone 13.

The comb-shaped element of Figure 2 is next bent, preferably while cold or under a relatively slight amount of heat, into the shape shown in Figure 3. From an inspection of Figure 3, it will be observed that the backbone 13 lies flat and provides a base for the binding, while the tips 19 of the fingers are bent to fit into the notched or cut out portions 18 of the backbone. It will thus be observed that there is no double thickness of binder material at this point for there is no overlapping of the ends of the fingers with the backbone. It will further be understood that the two relatively heavy scored lines 16 and 17 form the corners 20 and 21 while the lightly scored lines 15 lie along the inner surface of the fingers.

The underside of the backbone 13 and the tips 19 of the fingers 14 are then coated with an adhesive which is of the pressure-sensitive type as at 22 (see Figure 4).

The binder shown in Figure 4 is now arranged to be mounted in a cover member 23 (see Figure 5) which includes a front cover part 24, a rear cover part 25 and a back cover part 26. The inner surface of the back cover part 26 is covered with an adhesive material 27 which is of the pressure-sensitive type, and which will adhere to the adhesive coat 22 on the binder.

In order to employ the binder shown in Figures 3 and 4 of the drawings to bind a plurality of leaves (not shown) in the cover member 23, the fingers 14 are partially curled and the leaves which are provided with a series of slots along one of their marginal edges are threaded over the fingers 14. For simplicity of illustration the leaves have not been shown in the drawings, but it will be understood that before the fingers are completely closed, the leaves to be bound are hooked thereon.

The binder with the leaves on the fingers 14 is thereafter placed within the cover member 23 and the under portion of the binder with the coating of pressure-sensitive adhesive 22 thereon is pressed down against the back part 26 of the cover member 23 so that the adhesive 22 is pressed against the adhesive 27. The binder is thus se-

cured within the cover member 23 as shown in Figure 6 (the leaves being omitted, however, in order to show the full details of the binder itself). The combination binder and cover member unit is now complete.

It is to be understood that the cover member 23 may be formed of any suitable material such as cloth, paper, fiber, elastic-glass, plasticized Vinylite sheeting, Cellophane or other plastic material. Indeed, a particularly effective and decorative combination binder and cover member unit may be obtained by using a plastic cover member and a plastic binding element since the entire unit in this case will be formed of plastic material and may be given a highly ornamental appearance and effect.

A second embodiment of the invention is shown in Figure 7 of the drawings, wherein a binder such as that shown in Figures 3 and 4 is secured to a flat back plate 28 with adhesive 29 or other suitable binding material. In the form shown in Figure 7 the backbone 13 does not mate with the ends 19 of the fingers 14 but is slightly spaced therefrom.

Figures 8 and 9 of the drawings illustrate a third embodiment of the present invention. Referring first to Figure 8, a comb-shaped form is cut from a blank of plastic or other material and said form includes a backbone 30, a plurality of long fingers 31 which extend from one edge of the backbone 30 and are integral therewith, and a second set of relatively short fingers 32 which extend from the opposite edge of the backbone 30. In this form of the invention the long fingers 31 are provided with a plurality of transversely extending light score lines 33 but in this form of the invention these light score lines 33 also extend across the backbone 30. The ends of the relatively long fingers 31 are each provided with a relatively heavy score line 34 which corresponds to the heavy score line 17 of the first embodiment of the invention. The short fingers 32 are also provided with a relatively heavy score line 35 which is substantially in line with the edge of the backbone 30 from which the fingers 32 extend.

The comb-shaped blank as shown in Figure 8 is then bent into a binder as shown in Figure 9. As is clearly shown in Figure 9, the backbone 30 is given the same curvature as the long fingers 31. By virtue of the light scoring on one surface of the blank form as shown in Figure 8, this curvature may be given the backbone 30 as well as the long fingers 31 without raising the temperature of the plastic material forming the blank. The short fingers 32 are sharply bent along their heavy score lines 35 and the tips 36 of the long fingers 31 are similarly sharply bent along their heavy score lines 34 to provide a meeting portion which may be seated on the short fingers 32 and secured thereto by any suitable means, such, for example, as a pressure-sensitive adhesive.

In Figure 10 of the drawings I have illustrated a form of binding element 37 which has been formed from a comb-shaped blank having a backbone 38, a plurality of short fingers 39 and a plurality of transversely scored long fingers 40. The short fingers 39 extend inwardly at a sharp angle to the backbone 38, the long fingers 40 extend around in the same general curve as the backbone with the exception that their tip portions 41 are bent at a sharp angle with respect to the main portion so as to be seated on the short fingers 39. This binding element is similar to the binding elements described in connection

with Figures 8 and 9 of the drawings with the exception that the portions 39 and 41 do not lie along a radius of the circle formed by the binding element. The portions 39 and 41 are thus arranged to be disposed adjacent one of the end sheets of the stack of sheets 42 to be bound. A pressure-sensitive adhesive is put on the fingers 39 as at 43 and on the under surface of the tip portions 41 as at 44. After a stack of sheets 42, including cover members 42a, are placed on the fingers 40, the ends 39 and 41 are pressed together and the assembly is complete, as shown in Figure 11.

In Figures 12 and 13 of the drawings another form of binding element is shown which is in the form of a tubular element having a backbone 45 and a plurality of fingers 46. These fingers 46 are curled to their shape as shown in Figure 12 by providing a plurality of transverse scorings 15 on one surface thereof, as described in connection with Figure 2. In this form of binder a pressure-sensitive adhesive stripe 47 is placed along the inner surface of the marginal edge of the backbone 45 while confronting stripes of pressure-sensitive adhesive are placed on the outer surface of the finger tip portions as at 48. After the leaves have been assembled on the fingers 46 the fingers 46 are curled to their final shape and the portion of the fingers bearing the pressure-sensitive adhesive 48 is pressed against the adhesive 47 on the marginal edge portion of the backbone 45. The assembly is then complete, as shown in Figure 13.

In Figures 14 and 15 of the drawings another form of binding is shown in which the binding element has a flat backbone 49 having a lip portion 50 bent at right angles thereto. Extending from the backbone 49 on the opposite edge from the lip 50 is a plurality of fingers 51 having transverse scores 15 upon one surface. Each of the fingers 51 includes a substantially straight portion 52, a curved portion 53, and an inturned tip portion 54. A stripe of pressure-sensitive adhesive is applied to the inner surface of the lip 50 as at 55, and also on the immediate adjacent portion of the main body of the backbone, as at 56. A stripe of pressure-sensitive adhesive is placed on the outer surface of the tip 54 of each finger 51 as at 57, and is also placed on the outer surface of the adjacent body portion of the fingers 51 as at 58. After a stack of sheets 42 and cover members 43 have been assembled on the fingers 51 the fingers are closed with the stripe of pressure-sensitive adhesive 57 on each finger pressed into tight engagement with the stripe of adhesive 56 on the backbone 49 and also with the stripe of adhesive 58 on each finger pressed into tight engagement with the stripe of adhesive 55 on the lip 50. This forms a very secure binding assembly, as shown in Figure 15.

While I have shown particular embodiments of my invention, it will, of course, be understood that I do not wish to be limited thereto, since many modifications may be made, and I, therefore, contemplate by the appended claims to cover all such modifications as fall within the true spirit and scope of my invention.

I claim as my invention:

1. A binding element having a backbone, and a plurality of fingers extending therefrom, each 70 of said fingers having a plurality of relatively

light score lines extending transversely thereacross and providing a region of light score lines over substantially the entire length of each of said fingers, and a pair of relatively heavy score lines on said fingers extending transversely thereacross, one of said heavy score lines being substantially at the base of each of said fingers where it extends from said backbone and the other of said heavy score lines on each of said fingers being located in proximity of the tip of said finger, said fingers being arcuately curved throughout said region of light score lines and being sharply bent at each of said heavy score lines, and means for holding the tips of said fingers in close proximity to said backbone.

2. A binding element having a substantially flat backbone, a plurality of loop-shaped fingers extending therefrom, said backbone having a plurality of notches whose shape is complementary to the shapes of the ends of said fingers, a substantially flat backing member, and means for securing said backbone and said ends of said fingers to said backing member with said ends of said fingers disposed in mating relation with said notches in said backbone.

3. A ring binder having a substantially flat backbone, a plurality of integral fingers extending from one edge thereof and terminating in tip portions in proximity to the opposite edge thereof, a substantially flat backing member on which said backbone and said tip portions of said fingers are seated, and means for securing said backbone and said tip portions of said fingers to said backing member.

4. A ring binder having a flat backbone which lies in substantially a single plane, a plurality of integral fingers extending from one edge of said backbone, said fingers being bent in the form of open loops and terminating in tip portions in proximity to the opposite edge of said backbone, said tip portions being disposed in the same plane as the plane of said backbone, and a backing member adhesively secured to said backbone and to said tip portions of said fingers.

5. A ring binder having a flat backbone which lies in substantially a single plane, a plurality of integral fingers extending from one edge of said backbone, said fingers being bent in the form of open loops and terminating in tip portions in proximity to the opposite edge of said backbone, said tip portions being disposed in the same plane as the plane of said backbone, a backing member, and pressure-sensitive adhesive means for securing said backing member to said backbone and to said tip portions of said fingers.

6. A ring binder having a flat backbone which lies in substantially a single plane, a plurality of integral fingers extending from one edge of said backbone, said fingers being bent in the form of open loops and terminating in tip portions in proximity to the opposite edge of said backbone, said tip portions being disposed in the same plane as the plane of said backbone, a backing member, and pressure-sensitive adhesive means for securing said backbone and to said tip portions of said fingers, each of said fingers being transversely scored on one surface over the major portion of its length.
